CLAIM

The ornamental design for a USB cable, as shown and described.

DESCRIPTION

FIG. 1 is a front, right and top perspective view of a USB cable, showing my new design;

FIG. 2 is a rear, left and bottom perspective view thereof;

FIG. 3 is a perspective view thereof, showing the USB cable in a state of open.

FIG. 4 is a front view thereof;

FIG. 5 is a rear view thereof;

FIG. 6 is a left side view thereof;

FIG. 7 is a right side view thereof;

FIG. 8 is a top plan view thereof;

FIG. 9 is a bottom plan view thereof;

FIG. 10 is an enlarged view of the portion labeled "10" in FIG. 2 thereof; and,

FIG. 11 is an enlarged view of the portion labeled "11" in FIG. 2 thereof.

The broken lines shown in the drawings illustrate portions of the USB cable that form no part of the claimed design.

The dot-dash broken lines depict the boundaries of the enlargements that form no part of the claimed design.

1 Claim, 11 Drawing Sheets
